UNITED STATES PATENT OFFICE.

CAMILLE A. TURCOTTE, OF CHICAGO, ILLINOIS.

COMBINED CORSET AND TROUSERS SUPPORTER.

Application filed May 18, 1923. Serial No. 639,911.

To all whom it may concern:

Be it known that I, CAMILLE A. TURCOTTE, a citizen of the United States, residing at Chicago, in the county of Cook and State of Illinois, have invented new and useful Improvements in Combined Corset and Trouser Supporters, of which the following is a specification.

This invention relates to a combined corset and trousers supporter particularly adapted for men.

An object of the invention is to provide a band adapted to encircle the body at the hips and above the hips to act as a trousers supporter and to support the abdomen and the back.

Another object of this invention is to provide a body encircling band having pads attached to the hip portions for supporting and holding the trousers in proper position so they will make a neat appearance on the wearer.

A further object of the invention is to provide a body encircling band with stiffening ribs disposed at an angle in the band so positioned that they will effectually support the abdomen and the back over the portion where the kidneys are located.

The invention includes other features which are pointed out in detail with the construction of the band in the following description and claims and illustrated in the accompanying drawing, in which,

Figure 1 is a front view of the invention positioned on the wearer,

Figure 2 is a similar view showing the back portion of the band on the wearer,

Figure 3 is an enlarged detail view of the right half of the band,

Fig. 4 is a side elevation illustrating the inner side of one of the sections of the band.

Figure 5 is a detail section showing the pad construction.

—1— indicates a body encircling band formed in halves and provided in the rear portion with lacing strips —2— adapted to receive a lace —3— for fastening the halves of the band together in the rear. Fastener strips —4— are provided at the forward juncture of the halves of the band and carry separable fasteners —5— to removably fasten the band together so that it may be easily applied and removed from the body. Each half of the band is constructed of a plurality of longitudinal members —6— connected and held in spaced re-

lation by transverse members —7—. The lower longitudinal member —6— of each half is provided in the central portion with an elastic section —8— adapted to compensate for the large dimension about the hips when the band is in position on the wearer.

Each half of the band is provided in the portion which overlies the abdomen with a stiffening rib —9— forming a brace and support therefor and in the portion near the lacing strips —2— with a stiffening rib —10— fitting the small of the back and overlying the kidneys for holding the same in place. It will be seen that the stiffening strips 10 not only brace the kidneys, but also prevent creasing of the band. Shoulder straps —11— provided with elastic sections —12— are attached to the band with the elastic sections in the rear and with an adjustable and removable connection —13— in the front portion which also has an elastic connection —14— with the front of the band, one band being attached to each half of the body encircling band. The straps are connected together by a strip —15— positioned just below the neck in the portion of the straps on the back.

Trouser supporting pads —16— are connected to the band —1— over the hip portions along the line indicated at —17— forming a connection with the band and are also connected in the front portion by stitching or otherwise as indicated at —18—. The body of the pad is formed of a tubular container —19— and a container —20— decreasing in width toward the front and back, each container being filled with stuffing material as indicated at —21— in Figure 5. These containers are stitched together and to the strip forming the connection —17— as clearly shown in Figures 1 and 3. The bead —19— or tubular container is provided to form a ledge adapted to receive the bottom edge of a belt ordinarily used for supporting the trousers which forms a stop to the further downward movement of the belt and the trousers, while the pad —20— fills out the hip portion of the trousers to make them hang properly on the wearer and present a neat appearance.

As above pointed out it will be clear that the band and the attached pads form a combined trouser supporter and body brace which may be easily and quickly applied or removed from the body and which will be comfortable to the wearer.

In the event that the separable fastener connection —5— is unfastened and the wearer still desires to wear the band an adjustable connection —22— is provided along the upper edge of the band to hold the same in position on the body but which will not bind the body as when the connection —5— is used.

What is claimed is:

- 10 1. A combined abdomen and trouser support comprising a waist encircling member having a pair of separate waist encircling bands, and separate hip pads of arcuate formation carried by the bands and being gradually decreased in thickness toward their lower edges and being decreased in width toward their ends, the ends of the pads being spaced substantial distances from each other, the upper edges of said 20 pads being provided with arcuate trouser

supporting ledges, said ledges being spaced from the upper edge of the waist encircling member whereby to permit of the engagement of the belt encircled portion of the trousers with the waist encircling member 25 above the ledges.

2. A combined abdomen and trouser support comprising a waist encircling member, spaced ledges secured to the waist encircling member between the upper and lower edges 30 thereof and adapted to limit the downward movement of the trouser supporting belt, the waist encircling member between the upper edges thereof and the ledges being free for engagement by the belt encircled portion of the trousers and hip pads depending from said ledges.

In testimony whereof I affix my signature.

CAMILLE A. TURCOTTE.
